(57) **CLAIM**

The ornamental design for a “grunt wheeze game call apparatus,” as shown and described.

DESCRIPTION

FIG. 1 is a rear perspective view of a “grunt wheeze game call apparatus” according to the present invention;

FIG. 2 is a front perspective view thereof;

FIG. 3 is a top view thereof;

FIG. 4 is a right side elevation view thereof;

FIG. 5 is a bottom view thereof;

FIG. 6 is a left side elevation view thereof;

FIG. 7 is an enlarged rear view thereof; and,

FIG. 8 is an enlarged front view thereof.

The broken line showing is included for the purpose of illustrating portions of the “article” and forms no part of the claimed design.
